UNITED STATES PATENT OFFICE

2,597,711

BUCKET ATTACHMENT FOR MINE SHAFT EXCAVATIONS

Edward J. Donald, Old Kildonan, Manitoba, Canada

Application September 10, 1948, Serial No. 48,646

1 Claim. (Cl. 37—135)

1

My invention relates to new and useful improvements in bucket attachments for shaft excavation, an object of my invention being to provide a device of the character herewithin described whereby the excavation of mine shafts and the like, and subsequent removal of the debris therefrom, is facilitated.

A further object of my invention is to provide a device of the character herewithin described which is readily assembled and dismantled from the excavating bucket.

A still further object of my invention is to provide a device of the character herewithin described which eliminates the necessity of separate excavating and elevating units.

Another object of my invention in conjunction with the foregoing objects is to provide a device whereby the entire process of excavating and elevating material may be carried out with only one unit of moving machinery at the bottom of the shaft, thereby rendering the working space substantially safer for the operators.

Another object of my invention is to provide a device of the character herewithin described which is readily adaptable for attachment to conventional excavating buckets.

A still further object of my invention is to provide a device of the character herewithin described, the use of which enables the loaded bucket to be positioned concentrically below the lifting tackle, thus avoiding any possibility of over-balance occurring to the bucket with subsequent possibility of injury to the personnel resulting therefrom.

A further object of my device is to provide a device of the character herewithin described which incorporates means whereby the depth of the excavating cut may readily be controlled by the operator.

Another object of my invention is to provide a device of the character herewithin described which is economical in manufacture, rigid in construction, and which otherwise is well adapted to the purpose for which it is designed.

With the foregoing objects in view, and such other objects and advantages as will become apparent to those skilled in the art to which this invention relates as this specification proceeds, my invention consists essentially in the arrangement and construction of parts all as hereinafter

more particularly described, reference being had to the accompanying drawings in which:

Figure 1 is a perspective view of my device showing the method of assembly to an adapted excavating bucket.

Figure 2 is a reduced end elevation of an excavating bucket showing the attachment wings and pins.

Figure 3 is a rear elevation of my device removed from the elevator bucket.

Figure 4 is a reduced fragmentary side view of my assembly mounted upon an adapted excavating bucket.

Figure 5 is a vertical section of Figure 4.

15 In the drawings like characters of reference indicate corresponding parts in the different figures.

In the initial excavation of mine shafts and the like, considerable equipment is necessary for the digging operation as well as for the removal of the debris from the bottom of the shaft. Due to the restricted area existing at the base of the shaft, relatively few operators can be present at one time without the risk of injury occurring from the various moving parts. Under these circumstances the initial digging of the shaft is time consuming, and, with the relatively high cost of labor, considerable expense is incurred in this operation.

30 Consequently I have designed the assembly hereinafter to be described which combines the excavating equipment with the removal bucket, there being only one bucket at the bottom of the shaft at one time during the digging operation.

35 The excavating assembly per se can be transferred readily from one bucket to another with the minimum loss of time, and requires relatively few operators at the base of the shaft.

Proceeding, therefore to describe my invention in detail, it will be seen, upon reference to the accompanying drawings, to comprise the conventional mine bucket 1, which is of cylindrical configuration, to which are welded the four longitudinally extending wings 2 situated around the circumference of the bucket body, and outstanding therefrom. For clarity, I have designated these wings as the upper pair 3 and the lower pair 4, and it will be observed that the individual wings of each pair are situated parallel one with the other.

Apertures 5 are provided in each wing substantially towards the bucket mouth 6, for the engagement of the excavating assembly collectively designated 7 as will hereinafter be described. The upper and lower right hand wings 3 and 4, with reference to the accompanying drawings, are provided with leaf springs 9 riveted thereto medially along the length thereof and situated adjacent the inner surface 10 of the wings. The engaging pins 11 extend outwardly from the distal ends of the leaf springs and are in registration with the corresponding apertures 5 in the wings through which they protrude under the normal bias action of the leaf springs.

The excavating assembly collectively designated 7 is removably attached to the bucket-body as will hereinafter be described, and comprises the scoop 12 having a curvature substantially similar to the lower perimetrical portion of the bucket-mouth, and being provided with the excavating teeth 13 on the leading edge thereof. Attached as by welding to the underside 14 and extending rearwardly therefrom are the lower engaging arms or tie-bars 15, the right-hand one of which is provided with the aperture 16 within the distal end thereof, and the left hand bar with a pin 17, designed for engagement with the corresponding wings 3 and 4. Pivotedly attached to the sides 18 and the scoop and extending upwardly therefrom are the connecting links 19 the upper ends of which engage with the outer ends 20 of the relatively short projecting lugs 21. These lugs are formed upon the extremities 22 of the transverse bar 23 which has the bar actuating component 24 extending rearwardly and at right angles thereto medially along the length thereof. The relatively short upper engaging arms or tie-bars 25 depend from the transverse bar 23 substantially towards the outer ends 22 thereof, and are capable of registration with the upper pair of wings 3, the right-hand arm being provided with the aperture 26 and the left-hand arm with the engaging pin 27.

The conventional lifting chain 28 spans the bucket-mouth being connected thereto by means of the riveted eyes 29 and the rear wall 30 of the bucket is provided with the attaching eye 31 to which may be connected the drag chain 32 for the excavating operation, as will hereinafter be explained.

Having therefore described my invention in detail, its method of application will now be presented.

Figure 1 of the accompanying drawings shows the bucket 1 together with the excavating assembly 7 attached thereto and in the horizontal position for use as an excavating unit. In this context it is to be noted that in the appended claims the bucket is defined as being in position for horizontal or drag action loading, and when in this position as illustrated in Figure 1, the horizontal axis of the bucket (indicated by the reference character 33) extends between the entrance plane and the rear wall 30. The assembly 7 is attached to the bucket by engaging the pins 27 and 17 within the corresponding apertures 5 of the upper and lower left-hand wings. The leaf springs 9, which normally exert an outward bias, should be moved inwardly, thereby allowing the apertures 26 and 16 of the right-hand upper and lower tie-bars 25 and 15 respectively to come in registration with the aforementioned pins 11. Release of the springs 9 will permit the pins 11 on the ends thereof to engage with the apertures

26 and 16 in the tie bars 25 and 15, thus connecting the assembly to the bucket.

The bucket, together with the excavating assembly, may now be drawn backwards and forwards across the base of the mine shaft (not illustrated) by means of conventional block and tackle situated in the walls thereof connected to the lifting chain 28 and the drag chain 32. During this operation the scoop engages with the ground and may be elevated or lowered with relation thereto by movement of the bar actuating component 24 controlled by the operator who stands upon the upper surface of the bucket.

Reference to Figure 1 of the accompanying drawings will show that if the component 24 is moved downwardly with relation to the bucket, the scoop 12 will be elevated through the medium of the aforementioned links 19 and 21 pivoting around the lower engaging pins 11 and 17. Conversely, movement of the component 24 in an upward direction away from the bucket will result in the scoop biting more deeply into the debris being excavated.

When the bucket 1 is full, the block and tackle chains may be disengaged whereupon the lifting chain 28 may be attached to the conventional hoist chain (not illustrated) controlled from the top of the shaft. This will enable the bucket to be rotated so as to stand on end whereupon the excavating assembly 7 may be detached therefrom by disengaging the pins 11 from the upper and lower tie-bars which enables the pins 27 and 17 to be removed from their corresponding apertures.

The excavating assembly may then be fitted to an empty bucket which may then proceed to excavate while the first mentioned bucket is being elevated to the top of the shaft for disposal of the contents thereof.

Since various modifications can be made in my invention as hereinabove described, and many apparently widely different embodiments of same made within the spirit and scope of the claim without departing from such spirit and scope, it is intended that all matter contained in the accompanying specification shall be interpreted as illustrative only and not in a limiting sense.

What I claim as my invention is:

In a mine bucket wherein the axis from entrance plane to rear wall is horizontal when the bucket is in operable position, for horizontal or drag action loading, a bucket-body and a scoop projecting therefrom, a pair of tie-bars extending between said bucket-body and said scoop to constitute adjustable attachment of said scoop to said bucket-body, said tie-bars being pivotally connected to said bucket-body, said scoop conforming substantially to the forward perimetrical portion of the bucket mouth, means for dragging said bucket in the desired direction and means coacting between said scoop and said bucket-body for raising and lowering said scoop with respect to said bucket-body, said means for raising or lowering said scoop comprising a horizontal bar lying normal to the said bucket-body axis and mounted for rotation upon said bucket-body at a locus thereabove, said mounting including a pair of engaging arms depending from said horizontal bar and pivotally connected to said bucket-body, a bar actuating component secured for rotation medially along the length of said horizontal bar and overlying the bucket-body, a pair of projecting lugs secured to said bar for rotation therewith, and a pair of downwardly extending links secured at their upper

ends to said lugs and at their lower ends to said scoop, and means for selective attachment and detachment of said scoop and said raising and lowering means from said bucket including pins extending from one of said engaging arms engageable with said bucket-body and from one of said tie-bars engageable with said bucket body, and a pair of spring-loaded pins resiliently connected to said bucket-body and normally engaging the opposite engaging arm and the opposite tie-bar under the influence of said spring-loading.

EDWARD J. DONALD.
